UNITED STATES PATENT OFFICE.

GEORGE AUGUSTUS WALL, OF PROVIDENCE, RHODE ISLAND.

COUNTING MECHANISM.

SPECIFICATION forming part of Letters Patent No. 738,962, dated September 15, 1903.

Application filed December 13, 1899. Serial No. 740,169. (No model.)

To all whom it may concern:

Be it known that I, GEORGE AUGUSTUS WALL, of Providence, in the county of Providence and State of Rhode Island, have invented an Improved Counting Mechanism, of which the following is a specification, reference being had to the accompanying drawings, in which—

Figure 1 is a plan view of my improved counting mechanism. Fig. 2 is a section on line 2 2 of Fig. 1. Fig. 3 is a front view of the counting mechanism shown in Figs. 1 and 2. Fig. 4 is a detail of one of the dials. Fig. 5 is a section on line 5 5 of Fig. 4. Figs. 6 and 7 are details hereinafter referred to.

My invention has for its object to construct a counting mechanism in which each dial may be disengaged from its operating mechanism and quickly returned to its initial or starting position from any other position it may occupy; and my invention in its best form is a counting mechanism comprising in its construction a dial which is loaded so that when the dial is unrestrained the load will cause it to take one definite position on its axis, and means for operating the dial step by step adapted to be disengaged from the dial preparatory to returning the dial to zero and to engage the dial when the dial is at zero.

The dials A A' A² A³ are each mounted to turn loosely on a rod b, supported at its ends in the sides of frame B. Gears a a' a² are fast to dials A A' A² and engage, respectively, gears d d' d² on sleeves f f' f², which are loose on a second rod F, which is also supported at its ends in the sides of frame B.

The sleeves f f' f² carry disks g g' g², each with a tooth, (see Fig. 7), which engages the notches in wheels h h' h², fast to dials A A² A³.

Fast to dial A is a ratchet-wheel a⁸, which is engaged by one end of a pawl a⁹, and the other end of pawl a⁹ is pivotally connected with an arm a¹⁰ of a rock-shaft a¹¹, and rock-shaft a¹¹ carries armature a¹² of magnet a¹³, so that when magnet a¹³ is energized pawl a⁹ is moved in one direction and partially rotates dial A. Spring a¹⁴ moves pawl a⁹ in the opposite direction when the magnet releases its armature. Spring-pawl a¹⁵, fast on rock-shaft J, serves to prevent dial A from turning back when pawl a⁹ is retracted by spring a¹⁴. Each dial is loaded by a weight, so that when

the dial is unrestrained it will assume a definite position on rod b and display the zero character, so that when all of the dials are freed they will all return automatically to their zero position, and in order to free the dials the sleeves f f' f² are mounted to slide on rod F, so that disks g g' g² may be moved sidewise into and out of engagement with wheels h h' h². As a means for conveniently moving all of the sleeves at one time I have shown a yoke K, which is mounted at its ends to slide on rod F and is connected to one arm of a bell-crank lever k, pivoted to a standard k', extending up from the base of frame B, and the other arm of lever k is connected by a pin-and-slot connection with the inner end of plunger k², so that plunger k² may be moved in one direction by hand to move yoke K and sleeves f f' f² lengthwise of rod F, while spring k³ moves those parts in the opposite direction.

It is necessary that the wheels h h' h² should be in proper relation with disks g g' g² when the latter are moved to reengage the wheels, in order that the disks and wheels will then come into proper mesh, and to accomplish this dials A A' A² A³ each has a boss a⁴, formed with flattened sides, engaged by spring a⁵, fast to rock-shaft J, journaled at its ends in the sides of frame B and connected by ears j with plunger k². Spring-pawl a¹⁵ acts on ratchet-wheel a⁸ to insure the correct position of dial A.

The purpose of the pin-and-slot connection between bell-crank k and plunger k² is to provide lost motion between the plunger k² and yoke K, so that when the plunger is pushed inwardly spring-pawl a¹⁵ and springs a⁵ will be moved out of engagement with their respective dials before yoke K is operated and so that when plunger k² is moved in the opposite direction springs a⁵ and a¹⁵ will be moved into engagement with their respective dials before yoke K is moved in the opposite direction to reengage disks g g' g² and wheels h h' h².

Projecting from the dials A A' A² A³ are pins a⁶, which are each so located that should its dial occupy the position shown in Fig. 6, with the weight x balanced above the axis of the dial, when plunger k² is operated the pin a⁶ will be in the path of its spring a⁵ or spring

pawl a^5 , which will engage the pin and partially rotate the dial enough to move the weight x out of balance, so that the force of gravity will return the dial to its zero position.

The operation is as follows: When the circuit through magnet a^3 is closed, pawl a^9 moves ratchet a^8 and dial A one step. After dial A has moved nine steps and while moving the tenth step it moves dial A' one step through gears a and d , sleeve f , disk g , and wheel h , fast to dial A', and the peculiar construction of disk g and wheel h prevents all danger of dial A' being moved too little or too much and also holds dial A' motionless until disk g has moved nine additional steps, when the tooth on disk g engages another notch in wheel h and moves wheel h and dial A' another step. This is also a feature of my invention, for, although disk g and its wheel h are well known and in common use, yet I am the first to combine them with the dial of a counting mechanism, and this feature of my invention is especially important where the dials are actuated suddenly or are for any reason liable to move too much or too little or to be moved when they ought not to move—that is to say, the disks $g' g^2$ and wheels $h' h^2$ keep the dials A' A² A³ in almost perfect relation each to the others and to dial A and not only prevent miscounting, but also keep the visible characters on the dial in line, and, moreover, the disengagement and reengagement of disks $g' g^2$ and wheels $h' h^2$ can be readily effected. When pawl a^9 engages one of the teeth of ratchet a^8 , the motion of ratchet a^8 on its axis carries pawl a^9 away from stop a^{16} and toward stop a^{17} , and any excess motion of ratchet a^8 and its dial A is prevented by stop a^{17} , as will be clear from Fig. 2. Spring-pawl a^{15} also aids in causing dial A to move the proper distance at each step and in holding dial A in exact relation with the other dials. After dial A has moved ten steps and caused dial A' to move one step dial A' remains stationary and is held in exact relation to the other dials by its wheel h' and disk g and gears $d d' d^2$ and $a a' a^2$ until dial A has made nine more steps; but when dial A makes its second tenth step dial A' is moved a second step by the tooth on disk g engaging the second notch in wheel h , and this is the operation until dial A is about to complete its tenth revolution, when dial A' is caused to complete one revolution and dial A² is at the same time moved one step, and this will be plain without further description as to dials A² and A³. When the dials A A' A² A³ indicate the highest number desired, it is necessary that the dials be reset each to zero, and this is done by pressing plunger k^2 . The first portion of the inward motion of that plunger carries spring-pawl a^{15} and spring a^5 away from ratchet a^8 and bosses a^4 and the further inward motion of plunger k^2 disengages disks $g' g^2$ from wheels $h' h^2$ by moving yoke K and

sliding sleeves $f f' f^2$ on rod F. This leaves dials A A' A² A³ free to be moved each to its zero position, and each of them falls (when loaded, which is the preferred means of moving the dials) to that position unless its center of gravity happens to be vertically over the axis of rod b; but each dial which happens to be so balanced is moved out of balance by the action of pawl a^{15} or spring a^5 on pins a^8 —that is, when plunger k^2 is pressed in, the dials (in the best form of my invention) are each returned to its zero position approximately by force of gravity, and when plunger k^2 is released its spring k^3 moves it in the opposite direction, and during the first part of the return motion of plunger k^2 yoke K remains stationary, but rock-shaft J makes its return stroke and brings the dials into their exact zero positions, so that when yoke K is moved during the latter part of the return motion of plunger k^2 the disks $g' g^2$ will each reengage and relock its wheel $h' h^2$ and the tooth on each disk $g' g^2$ will occupy its proper angular relation to the notches in its wheel $h' h^2$. This is for the reason that when the dials fall each to its zero position, each dial except A³, acting through its gear a , a' , or a^2 and through the gears d , d' , or d^2 , moves its sleeve $f f' f^2$, and thereby the angular motion of each disk $g' g^2$ and its sleeve $f f' f^2$ is the same as the angular motion of the dials and the wheels $h' h^2$, each fast to its dial.

It will now be clear that the main feature of my invention is disengaging the dials each from its operating mechanism in order that the dial may be set to zero and reengaging the dial with its operating mechanism when the dial is set to zero. The loaded dial and the combination of the primary dial with its secondary by means of a disk with one tooth which locks its wheel, except when the single tooth engages a notch in the wheel, are also important features of my invention; but it will be obvious that each one of these three may be used independently of the others and that their combination is also in itself another important feature of my invention.

What I claim as my invention is—

1. In a counting mechanism the combination of a dial whose center of gravity is disposed to cause the dial to take one definite position on its supporting-rod; and means to automatically move the dial on its axis when its center of gravity is in vertical alinement over the axis of its supporting-rod.

2. In a counting mechanism the combination of a loaded dial; means for moving that dial slightly when the load happens to be balanced over the axis of the dial; means for operating the dial step by step; and means to disengage and reengage the operating means.

GEORGE AUGUSTUS WALL.
